PACKAGED TOOTHBRUSH HOLDER AND TOOTHPASTE DISPENSER

Adolfo Rene Arquelles and Marcelino Moya, Jr.,
Tampa, Fla.

Application February 18, 1954, Serial No. 411,066

3 Claims. (Cl. 222—93)

Our invention relates broadly to dental hygiene devices and more particularly to a compact merchandisable package for toothbrushes and toothpaste and which is usable upon installation as a toothpaste dispensing device.

One of the objects of our invention is to provide a compact merchandisable package for toothbrushes and toothpaste the package being readily installable as a bathroom accessory for holding toothbrushes and a toothpaste dispensing tube in association with a mirror.

Another object of our invention is to provide a merchandisable package for toothbrushes and toothpaste dispensing tubes in which the casing of the package is substantially elliptical in cross-section providing supporting means for toothbrushes in the segmental portions at opposite ends of the casing and having mounting means for a toothpaste dispensing tube centrally of the casing.

Still another object of our invention is to provide a construction of package for enclosing toothbrushes and a toothpaste dispensing tube of substantially oval cross-section in which the opposite interior sides of the package include mounting means for toothbrushes while the central portion of the package provides mounting means for a toothpaste dispensing tube.

Still another object of our invention is to provide a compact merchandisable package for enclosing both toothbrushes and a toothpaste dispensing tube where the parts of the package may be inexpensively molded from plastic material for protecting the goods in shipment and providing a fixture which may be readily installed as a toilet accessory in a bathroom.

A further object of our invention is to provide a readily portable compact package which may be carried by family groups as a travelers' toilet accessory for detachable installation in hotels, motor courts, motels, and the like, for caring for the dental hygiene needs of the family traveling.

A still further object of our invention is to provide a construction of casing for a dental hygiene device for insuring the circulation of air through that part of the casing in which the bristles of the toothbrushes are exposed for facilitating drying of the bristles after use.

Other and further objects of our invention reside in the structural features of the compact merchandisable package as more fully described in the following specification by reference to the accompanying drawings, in which:

Fig. 1 is a vertical sectional view along the minimum axis dimension through the casing of the merchandisable package of our invention, the toothpaste dispensing tube being shown partially in side elevation, the view being taken on line 1—1 of Fig. 2;

Fig. 2 is a vertical sectional view through the casing of the merchandisable package along the maximum dimension lateral axis thereof, the view showing a portion of the toothpaste dispensing tube and the toothbrushes in elevation, the view being taken substantially on line 2—2 of Fig. 3;

2

Fig. 3 is a horizontal sectional view taken on line 3—3 of Fig. 2;

Fig. 4 is a horizontal sectional view taken on line 4—4 of Fig. 2;

5 Fig. 5 is a fragmentary view of a modified form of the top of the casing showing one manner of hingedly connecting a mirror thereto;

Fig. 6 is a horizontal sectional view through a modified form of our invention, the view being taken on line 10 6—6 of Fig. 7;

Fig. 7 is a vertical sectional view through the structure of our invention illustrated in Fig. 6, the view being taken substantially on line 7—7 of Fig. 6; and

Fig. 8 is a vertical sectional view taken substantially on line 8—8 of Fig. 6.

Our invention is directed to a construction of readily moldable casing which may be used as a compact package for enclosing toothbrushes and a collapsible tube of toothpaste. The package protects the toothbrushes and

20 the toothpaste during shipment and may be readily installed as a toilet fixture in a bathroom. The toothpaste tube is progressively collapsible from the exterior of the casing and when the toothpaste has been entirely used the toothpaste tube is readily removable and a replacement readily insertable. The cover of the package is

25 either hingedly connected with the casing or is wholly detachable therefrom for facilitating its use as a support for a viewing mirror contained in the cover. Compactness is secured by reason of the elliptical or oval

30 contour of the dental hygiene package of our invention. We have found that this shape occupies a minimum of space and yet provides for the mounting of toothbrushes in the interior opposite sides of the casing while the toothpaste dispensing tube is mounted centrally of the casing

35 between the toothbrushes. We have shown two arrangements for mounting the toothbrushes in the interior sides of the casing in one of which the toothbrushes are mounted facing the interior of the casing while in another of which the toothbrushes are supported in positions spaced from the side walls of the casing and directed toward the front and rear of the casing.

Referring to the drawings in more detail, reference character 1 designates the enclosing casing of the package of our invention. This casing is molded and is preferably formed from clear plastic through which the toothbrushes 2, 3, 4 and 5 and the collapsible tube of dental toothpaste indicated at 6 are readily visible. The casing 1 is elliptical or oval-shaped in lateral section as

40 represented more clearly in Figs. 3 and 4 and the toothbrushes are mounted adjacent the interior side walls forming the limits of the elliptical or oval-shaped casing along the maximum axis dimension. The minimum axis dimension of the casing extending between the front and rear walls is provided with a guide trackway represented at

45 7 at the rear wall and a vertical slot 8 at the front wall. The guide track 7 encloses an annular member 9 into which a transverse shaft 10 extends. The transverse shaft 10 is slotted intermediate its length as represented at

50 10a in Fig. 2 for receiving the flat metallic end 11 of the collapsible dental toothpaste tube 12 after the screw threaded end 14 has been passed through the inclined aperture 1a in the bottom of casing 1 and engaged in the screw threaded sleeve 15 externally of the bottom of the casing 1. The screw threaded sleeve 15 is detachably engaged over the depending screw threaded

55 end 14 of the toothpaste tube in lieu of the conventional screw threaded cap supplied on the dental toothpaste tube. The end 14 of the collapsible tube extends into the screw threaded sleeve 15 in alignment with the aperture

60 16 therein. The depending end of sleeve 15 is formed of reduced section and externally screw threaded for receiving the detachable cap 18; the cap 18 is connected

65 70 to the screw threaded sleeve 15. The screw threaded sleeve 15 is formed of reduced section and externally screw threaded for receiving the detachable cap 18; the cap 18 is connected

through a chain 19 fastened to the bottom of casing 1 by means of lug 20 as shown more clearly in Fig. 2. Accordingly, the conventional dental toothpaste tube 12 may be inserted into the interior of casing 1 through the open top thereof with the cover 21 removed and the end of the tube at 14 passed through aperture 1a and engaged by sleeve 15 covered by cap 18. When the end 11 of dental toothpaste tube 12 is inserted in slot 10a and wrapped around shaft 10 the contents of the dental toothpaste tube 12 are ready for ejection by removing cap 18 and revolving shaft 10.

The forwardly projecting end of shaft 10 passes through vertical slot 8 in casing 1 and is provided with a finger-grip knob 10b by which the metal of the collapsible dental toothpaste tube is rolled up and pressure applied in a downward direction for ejecting the dental toothpaste through aperture 16 onto the bristles of a toothbrush held facing upwardly beneath the aperture 16. The toothbrushes 2-5 are readily mounted interiorly of the casing adjacent the opposite sides thereof in longitudinally extending guideways which we have indicated at 22, 23, 24 and 25, into which the handles of the toothbrushes 2, 3, 4 and 5 respectively project. The guideways 22-25 are each slotted at 22a, 23a, 24a and 25a to facilitate entry and removal of the handles of the toothbrushes 2-5 within the compact space around the toothpaste tube 12. The bristles of the toothbrushes 2-5 are arranged in line with the horizontal apertures in the casing 1, represented at 26 and 27. The ventilating apertures 26 and 27 are aligned with the position in which the bristles of brushes 2-5 are maintained. The apertures are inclined upwardly to preclude, in so far as it is practical, the entry of foreign matter while permitting the circulation of air around the bristles for drying the bristles after use.

The cover 12 is provided with a mirror 28. A recess 21a is provided in the undersurface of cover 21 having the same contour as the elliptical section of the casing 1 for maintaining the cover 21 in position with respect to the upper periphery of the casing. Thus the cover 21 may be readily removed from casing 1 and the mirror used as an aid while cleaning the teeth.

In Fig. 5 we have shown a modified form of our invention wherein casing 1a is provided with a lug 1b adjacent the top thereof to which a hinged connection is made from cover 21' through an appropriate hinged lug 21b, whereby cover 21' may be moved to the position 21" while the device is in use and while the mirror 28 is being used. Groove 21'a coacts with the upper periphery of casing 1 when the cover 21' is closed.

The casing 1 is provided with a pair of rearwardly extending projections 29 and 30 into which there is anchored the suction cups 31 and 32 which enable the device to be detachably supported against any available vertical surface, such as represented at 33.

In Figs. 6-8 we have illustrated a modified form of our invention in which provision is made for mounting the toothbrushes 2, 3, 4 and 5 within the segments of the opposite sides of the casing 1, by means of molded segmental portions 34 and 35 disposed intermediate the opposite sides of casing 1 and the position occupied by collapsible tube 12. The segments 34 and 35 extend from the bottom of casing 1 to a position spaced below the top of the casing for a sufficient distance to maintain the bristles of the brushes 2-5 exposed to the circulation of air through the rows of apertures 26 and 27. The segmental portions 34 and 35 are provided with longitudinally extending guideways 22', 23', 24' and 25' which receive the handle ends of the toothbrushes, the guideways opening through slots 22'a, 23'a, 24'a and 25'a toward the interior walls of the opposite sides of casing 1 along the medium axis dimension of the casing. This arrangement facilitates the removal and insertion of the toothbrushes in a direction remote from the center of the casing for reducing obstruction to the insertion and

removal of the dental toothpaste tube 12. The other parts of the package are the same as described in connection with Figs. 1-4.

Our invention has been found very practical by reason of its compact assembly as a merchandisable package for both toothpaste and toothbrushes and while we have described our invention in certain preferred embodiments we realize that modifications may be made and we desire that it be understood that no limitations upon our invention are intended other than may be imposed by the scope of the appended claims.

What we claim as new and desire to secure by Letters Patent of the United States is as follows:

1. A packaged toothbrush holder and toothpaste dispenser comprising a casing of substantially elliptical cross section having an integral bottom portion and a movable top portion for normally closing the top of said casing, longitudinally extending partition members disposed across the interior sides of said casing and spaced from the interior surfaces of the side walls of said casing and extending from said bottom portion to a position spaced from the top portion of said casing for a distance approximately equal to the length of the brush portions of the toothbrushes and defining with the adjacent side walls vertically disposed compartments of substantially segmentally shaped transverse section and longitudinally extending guideways formed in said partition members for receiving and embracing the handles of the toothbrushes throughout the lengths thereof in vertically depending positions in the opposite interior sides of said casing for maintaining the brush portions of said toothbrushes in positions with the bristles thereof spaced from the walls of the casing, means disposed centrally of said casing intermediate said partition members for mounting a toothpaste dispensing tube in inverted position, and means coacting with the front and rear walls of said casing for progressively collapsing said toothpaste dispensing tube for ejecting toothpaste through an orifice in the bottom portion of said casing, said side walls being apertured adjacent the brush portions of the toothbrushes to facilitate the circulation of air around the bristles of said toothbrushes.

2. A packaged toothbrush holder and toothpaste dispenser comprising a casing closed at the bottom and having a removable top and a vertically extending tubular enclosing wall structure with a lateral cross section that is substantially elliptical in contour with the maximum transverse dimension thereof extending between the opposite side walls of the casing and a minimum transverse dimension extending between the front and rear walls of said casing and longitudinally extending curved partitions disposed interiorly of said casing and spaced from the interior surfaces of the opposite side walls of the casing, said curved partitions being integral with the bottom of said casing and terminating short of the top of said casing for a distance approximately equal to the length of the brush portions of toothbrushes insertable into and removable from said casing, said partitions and the interior surfaces of said side walls defining vertically disposed compartments of substantially segmentally shaped transverse section, said partitions having longitudinally extending guideways formed therein for receiving and embracing the handles of the toothbrushes throughout the lengths thereof interiorly of said casing in substantially vertically disposed positions spaced from the interior surfaces of the opposite interior walls of the sides of the casing and remote from the central portion of said casing, said side walls being apertured for the circulation of air around the bristles of the toothbrushes.

3. A package for dental toothpaste and toothbrushes as set forth in claim 2 in which said longitudinally extending guideways are directed outwardly from said partitions toward the side walls of said casing and are longitudinally slotted through the length of the guideways for facilitating the insertion and removal of the toothbrushes

into and from said casing in the space between the side walls of said casing and said partitions.
